UNITED STATES PATENT OFFICE

2,614,284

CARPET FASTENER

Arnold C. Eichin, Elmhurst, Ill., assignor to
 Arnold C. Eichin, Incorporated, Chicago, Ill., a
 corporation of Illinois

Application January 10, 1949, Serial No. 70,120

7 Claims. (Cl. 16—10)

1

This invention relates to improvements in a carpet fastening device particularly adapted for use in the laying of stair carpet.

It is an object of my invention to produce a carpet fastener particularly for use in laying stair carpet which shall function to draw the carpet tightly into the joint between the riser and the tread and hold the carpet securely in such position.

It is a further object of the invention to provide a device of the character described which shall be of simple and relatively inexpensive construction so that it may be left in place in the stairs concealed by the carpet.

Still another object of the invention is to provide a carpet fastener which is easily operable to release the carpet from the holding device whenever it is desired to take up the carpet for cleaning or moving.

Still another object of the invention is to provide a carpet fastening device comprised of two hingedly connected members adapted to lie against the riser and the tread and which are provided with a simple manually operable mechanism for changing their angular relation so as tightly to draw the carpet into place and securely to hold it.

Other objects of the invention and the advantages thereof will more fully be brought out as the description of the invention proceeds.

In the accompanying drawings, I have illustrated a practical embodiment of my invention but it is to be understood that the drawings are illustrative merely and that I do not confine myself to the particular details of construction shown therein. Once the principle of the invention is understood, it will readily occur to those skilled in the art how its structural features may be changed without sacrificing the advantages of the invention or departing from the scope thereof as defined in the appended claims.

In the drawings:

Fig. 1 is a fragmentary view in perspective of a portion of a stair with a part of the carpet broken away to show the location of my carpet fastening device;

Fig. 2 is a sectional view on an enlarged scale, taken substantially on line 2—2 of Fig. 1;

Fig. 3 is a sectional view similar to Fig. 2 but showing the parts of the fastening device in the initial position they occupy before they are brought to the position of Fig. 2;

Fig. 4 is a plan view of my device;

Fig. 5 is a fragmentary plan view showing the operating mechanism in the open position it will occupy when the parts are as shown in Fig. 3;

Fig. 6 is a plan view of the operating mechanism, parts being broken away to show the interior construction; and

Fig. 7 is a view similar to Fig. 6 showing the

2

operating mechanism in closed or locked position.

Referring now to the drawings, my fastening device comprises a pair of members 10 and 11 which are preferably made of metal of sufficient gauge to give them strength and rigidity, yet light enough to reduce cost and make them easy to handle.

It will be observed from an inspection of Figs. 2 and 3 that the said members 10 and 11 are somewhat bent or bowed longitudinally and substantially centrally for a purpose presently to be indicated.

The members 10 and 11 are interconnected by suitable hinges 12 which are preferably integrally formed with the said members.

The hinges are provided with springs 13 (see Fig. 5) which tend to hold said members 10 and 11 in the open position shown in Fig. 3.

Each of the members 10 and 11 is provided with a plurality of carpet-engaging hooks or points 14 which are preferably formed by cutting out portions of said members 10 and 11 and then swaging said cut-out portions into the form of hooks or points as shown in the drawings.

It will be noted that the shape of the said points or hooks 14 is such that, when considered in conjunction with the bent or bowed part of the members 10 and 11, said hooks engage the lower surface of the carpet in the manner shown in Fig. 2.

In order to operate the device so as to force the members 10 and 11 from the position shown in Fig. 3 to that shown in Fig. 2, I employ a pair of operating devices generally indicated by the reference numeral 15, there being one such device at each end of the members. Each of said operating devices 15 comprises a metal member bent substantially at right angles to provide a vertically extending portion 16 which, when the device is in position, will lie against the stair riser, as shown in Figs. 2 and 3. At its upper end, the part 16 is provided with a hook 17 adapted to enter a slot 18 formed near the upper edge of the member 11. Said part 16 also has a pair of hook-like members 19 which engage over the top edge of the part 16.

The horizontally extending part of the operator 15 is indicated by the reference numeral 20. Said part 20 is provided with a slot 21 which forms a guide for the movement of a pressure member 22 which has upwardly extending projections adapted to engage the forward edge of the member 10.

It will thus be seen that the operating member has a part engaging the upper edge of the member 11 and another part engaging the forward edge of the member 10. By manipulation, as presently to be described, pressure is applied to the two edges of the members 10 and 11 so as to cause them to swing about the hinges 12 from

the position shown in Fig. 3 to the position shown in Fig. 2. As is evident from an inspection of these figures, said members 10 and 11 initially extend away from each other at an angle of more than 90°. In the operation of the device, it is desirable to bring said members together so that when in operative position they will be at an angle of 90° or less to each other.

This is accomplished by moving the member 22 in the slot 21 of the operating members 15. By particular reference to Figs. 6 and 7, it will be seen that the member 22 is pivoted as at 23 to an operating lever 24. Said lever 24 is pivoted at 25 to a link 26 which, in turn, is pivoted at 27 to the member 20.

Thus, as viewed in Fig. 6, the member 22 is at the forward end of the slot 21 and the operating lever 24 extends outwardly. When said lever 24 is moved inwardly, its pivoted end 23 moves rearwardly so that the member 22, pressing against the member 10, moves the latter into position substantially horizontally with respect to the stair tread. The closed or operative position of the operating device is that shown in Fig. 7.

In the operation of the device, one of my fasteners will be provided for each joint between a tread and riser. The devices are adapted to be left in place and consequently the length of each device is somewhat less than the width of ordinary stair carpet (usually 27 inches) so that when the carpet is in place the fastening device will be concealed.

The first step in the application of the invention is to secure the operating devices in place. For this purpose each device is provided with an opening through which a suitable fastening element, such as screws 28, may pass into the joint between the tread and the riser as shown in Figs. 2 and 3. It will be understood, of course, that the hooks 17 have been passed through the slots 18 in the vertical member 11 so that they will be accurately placed. When this is done the device will occupy the position shown in Fig. 3. Then the operator pulls down on the carpet so that the hooks 14 enter into the lower layer or bottom surface of the carpet. When this is being done, the operating devices are in the position shown in Fig. 6, that is to say, with the operating levers 24 extending outwardly.

Now all that the operator has to do is to move the levers 24 inwardly, thus causing the engaging members 22 to travel in the slot 21, thereby forcing the members 10 and 11 to swing about the hinges 12 against the action of the springs 13 until they occupy the position shown in Fig. 2.

During this movement the carpet is stretched over the projecting edge of the upper tread and down along the riser and is firmly held in that position by the operating or locking devices.

To remove the carpet, as for cleaning, or when it is desired to shift the carpet where the tread surface has been worn, it is necessary only to reach under the carpet and grasp the levers 24 and swing them outwardly to the position shown in Fig. 6. When this is done, it is very easy and simple to lift the carpet from the impaling hooks 14.

Inspection of Fig. 2 will make it plain that the said hooks 14 are so related to the bent surfaces of the members 10 and 11 that said hooks 14 will penetrate the carpet only sufficiently to hold it securely and will not pass clear through as is done with other devices.

The use of my device will make the laying of stair carpet much easier than has heretofore

been possible. It will obviate large and unsightly carpet tacks which also very often ruin the stair carpet by making large holes in it.

Once my devices have been installed, they will last as long as the stairs and can therefore be employed from time to time as stair carpet is changed.

Considering the ease of installation, and the rapid and secure way in which the carpet is stretched and held in place, it will be apparent to those skilled in the art that I have provided a device of great utility and economy. Its advantages will also be especially appreciated when the time comes to lift the carpet which can be done more easily and effectively with my device than any other securing means with which I am familiar.

I claim as my invention:

1. A stair carpet fastener comprising a pair of hinged members, each of which is bent longitudinally, carpet-engaging projections on said members along the bend therein, and means for drawing said members together whereby said carpet-engaging projections engage the lower surface of the carpet and draw the same tightly into the joint between said members.

2. A stair carpet fastener comprising a pair of hinged members, one of said members adapted to lie against the riser and the other against the tread, and mechanism operable to change the angular relation of said members, said mechanism comprising a part lying against the riser and connected to the first mentioned member and another part lying against the tread and slidably engaging the second mentioned member.

3. A stair carpet fastener comprising a pair of hinged members, one of which is adapted to lie against the riser and the other against the tread, carpet-engaging projections on said members, and mechanism connecting said members at their ends and operable to swing said members toward each other about their hinges whereby said carpet-engaging projections may enter a carpet and draw the same tightly toward the joint between said members.

4. A stair carpet fastener comprising a pair of hinged members, one of said members adapted to lie against the riser and the other against the tread, spring means urging said members apart and away from the riser and the tread, and manually operable means for moving said members against the action of said spring means substantially into contact with the riser and the tread.

5. A stair carpet fastener comprising a pair of hinged members, one of said members adapted to lie against the riser and the other against the tread, spring means urging said members apart and away from the riser and the tread, manually operable means for moving said members against the action of said spring means substantially into contact with the riser and the tread, said manually operable means comprising a bracket having a portion lying against the riser and engaging one of said members and a portion lying against the tread and having a pressure element slidably engaging the other member.

6. A stair carpet fastener adapted to be secured at the juncture of a stair tread and an upstanding riser, comprising a pair of hinged members, longitudinal carpet-engaging members, spring means urging said members to an open position, a pair of spaced apart L-shaped brackets adapted

to be secured to the juncture of a stair tread and a riser, means secured to the upper end of each of the upstanding legs of said L-shaped brackets pivotally supporting one of the members of said pair of hinged members at opposite longitudinal ends thereof, a pressure member for each of said brackets engaging the other of the members of said pair of hinged members and slidably mounted for movement between first and second positions along the horizontal leg of said L-shaped brackets to move said hinged members from said open position toward each other against the bias of said spring means to a closed position, and a pair of manually operable levers pivotally mounted respectively on each of the horizontal legs of said L-shaped brackets selectively controlling movement of said pressure members between said first and said second positions. 15

7. A stair carpet fastener adapted to be secured at the juncture of a stair tread and an upstanding riser, comprising a pair of hingedly connected longitudinal carpet-engaging members, spring means urging said members to an open position, a pair of spaced apart L-shaped brackets adapted to be secured to the juncture of a stair tread and a riser, means secured to the upper end of each of the upstanding legs of said L-shaped brackets pivotally supporting one of the members of said pair of hinged members at opposite longitudinal ends thereof, a pressure member for each of said brackets engaging the other of the members of said pair of hinged members and slidably mounted for movement between first

and second positions along the horizontal leg of said L-shaped brackets to move said hinged members from said open position toward each other against the bias of said spring means to a closed position, a pair of manually operable levers pivotally mounted respectively on each of the horizontal legs of said L-shaped brackets, selectively controlling movement of said pressure members between said first and said second positions, and teeth on said pair of members adapted to grasp a fold in the stair carpet and to draw it toward the juncture of the stair tread and the riser as said hinged members are moved from open to closed positions. 10
